UNITED STATES PATENT OFFICE.

GEORGE CAPRON, OF BELOIT, WISCONSIN.

HOISTING DEVICE.

1,237,297.

Specification of Letters Patent. Patented Aug. 21, 1917.

Application filed December 30, 1916. Serial No. 139,732.

To all whom it may concern:

Be it known that I, GEORGE CAPRON, a citizen of the United States, residing at Beloit, in the county of Rock and State of Wisconsin, have invented certain new and useful Improvements in Hoisting Devices; and I do hereby declare the following to be a full, clear, and exact description of the invention, such as will enable others skilled 10 in the art to which it appertains to make and use the same.

This invention relates to a hoisting device and is primarily designed for use in lifting the body of a vehicle from the running gear.

The main object of the invention is the provision of a device of this character adapted to be used to lift a hay rack from the vehicle running gear.

20 Another object of the invention is the provision of means whereby the hay rack may be held in suspended position.

A further object of the invention is to provide a hoisting device embodying a 25 frame consisting of spaced side bars, the forward ends of which are each provided with an upwardly inclined board or frame which is adapted to engage a roller carried by the forward portion of the hay rack and 30 disposed on opposite sides, so that as the running gear is drawn in between the side bars, the forward end portion of the hay rack will be caused to rise upwardly sufficiently to disengage it from the front bolster by the rollers carried thereby riding up 35 the inclined board or frame.

A still further object of the invention is the provision of a frame upon which is mounted a hoisting lever, the rear end of 40 the hoisting lever carrying the hay rack and adapted to engage the rear end of the hay rack whereby it may be elevated into the same plane as the front end or sufficiently to disengage the rear end from the 45 rear bolster.

A still further object of the invention is to provide means for locking the forward end of the lever in actuated position to hold the hay rack in suspended position.

50 With these and other objects in view as will appear as the description proceeds, the invention comprises the various novel features of construction, combination and arrangement of parts as will be more fully 55 described hereinafter, and set forth with particularity in the appended claim.

Referring to the drawings,

Figure 1 is a perspective view of my improved hoisting device, and

Fig. 2 is a side elevation of the same with 60 a wagon running gear disposed therein and showing the hay rack carried by it disposed in elevated position above it.

Similar characters of reference are used to denote like parts throughout the accompanying drawings and the following description.

Referring more particularly to the drawings, my improved construction of hoisting device is shown to consist of spaced up- 70 rights 1, the upper ends of which are each provided with a concavity 2. Extending horizontally across and disposed in the concavities 2 of the uprights is a rock bar 3, which in this instance is shown to be circular in cross section.

Detachably connected to this rock bar 3 intermediate its ends is an actuating lever 4, this lever being connected to the bar through the medium of a bolt 5 that is ex- 80 tended through the lever and the rock bar and securely retained in position by a nut 6. The rear end of the actuating lever is provided with a cable or other flexible element 7 that has its upper end suitably at- 85 tached to the rear end of the lever, and in this instance is shown to be attached to an eye 8 carried by the underneath surface of the lever. The lower end of the flexible element 7 has attached thereto a supporting 90 hook 9.

As shown the actuating lever 4 is fulcrumed upon the uprights 1 adjacent its rear end so as to provide the desired amount of leverage. The forward end of the lever 95 has attached to it a cable or flexible element 10, the upper end of which is suitably attached to the lever, and in this instance is attached to an eye 11 secured to the lever, while to the opposite or lower end of the 100 flexible element is attached a retaining hook 12.

Extending forwardly and upwardly from each of the uprights 1 is a side bar 13, which terminates in the horizontally disposed forward end bar 14, each of these bars 14 being supported by an upright post 15. In order to firmly support the forward end of each of the bars 14 and also to brace the post 15, I provide a brace bar 16 that is 110 extended diagonally from the post 15 upwardly to the forward end of the bar 14.

Each of these spaced side bars 13 and 14 carry at their inner opposed forward ends inclined boards or frames 17. As shown each of these boards or frames consist of a substantially elongated board that embodies an upwardly and forwardly inclined portion 18, which terminates in a horizontally disposed portion 19. A roller 21 is mounted on each side of the forward portion of the hay rack 22 and are designed to engage and ride up the inclined boards 17.

This hay rack 22 is of the usual and ordinary construction and embodies the overhanging sides 23 that are supported by the usual cross frame members 24 carried by the bottom 25. Each of the rollers 21 is securely attached to the underneath surface of the overhanging sides 23 so as to be directly in alignment with each inclined board.

The hay rack 22 is mounted upon and carried by the ordinary construction of wagon running gear 26 which embodies the usual construction of front and rear bolsters 27 and 28 respectively, the hay rack being provided with transversely extending cleats 29 arranged in spaced relation at opposite ends thereof so as to embrace each of the bolsters so as to securely hold and retain the hay rack in position upon the running gear.

When it is desired to remove the hay rack from the running gear, the running gear and hay rack carried by it are drawn under the rock bar 3 and between the spaced uprights 1 and the spaced side bars 13 into the position shown in Fig. 2. As it is drawn into the position shown, each of the rollers 21 will engage the inclined board or frame carried by each side frame 13, and as the running gear continues to move forward, the rollers 21 will ride up these inclined boards or frames a sufficient distance to raise the hay rack off of the front bolster.

The front end of the hay rack now having been elevated a proper distance, the rear end is elevated to the same plane by engaging the supporting hook 9 beneath the rear cross member 24, and grasping the forward

portion of the actuating lever and pulling down upon the same sufficiently to engage the retaining hook 12 beneath the adjacent cross frame member 24, which will serve to hold and retain the lever in actuated position or in other words will serve to hold and retain the rear end of the hay rack in elevated position. The hay rack having now been suspended in elevated position, the running gear can be freely removed from beneath the rack.

When it is desired to again place the hay rack upon the running gear, the latter is drawn in or backed into position beneath the hay rack, whereupon the rear end of the hay rack is lowered into position upon the rear bolster 28. This having been done the wagon is backed out of the device, and as it is backed out the rollers 21 will ride downwardly over the inclined boards or frames 17 until the front end of the hay rack descends into engagement with the front bolster of the running gear.

What I claim is:—

A hoisting device comprising a pair of uprights between which a vehicle is adapted to be driven, side bars inclined upwardly from said uprights, a horizontal bar extending forwardly from each inclined bar, anti-friction means carried by the forward end of the vehicle body and adapted to ride up said inclined side bars and rest upon said horizontal bars to support the forward end of the vehicle body in an elevated position against casual backward movement, means mounted on said uprights to elevate the rear end of the vehicle body into the same plane with the forward end, and means for securing said rear end of the vehicle body in an elevated position.

In testimony whereof I have signed my name to this specification in the presence of two subscribing witnesses.

GEORGE CAPRON.
